**OFFSHORE PLATFORM AND METHOD OF
ERECTING THE SAME**

Patrick J. Doody, New Orleans, La., and Benjamin L. Geopfert, Houston, Tex., assignors to Shell Oil Company, a corporation of Delaware

Filed Jan. 30, 1956, Ser. No. 562,169

6 Claims. (Cl. 61—46)

This invention relates to offshore platforms of the type used in well drilling operations, such as drilling platforms which may be positioned at a desired location for drilling a well, or production platforms which may be positioned around a wellhead and its casing after the well has been drilled.

During the past several years considerable interest has been shown in drilling oil wells in offshore locations, particularly in the Continental Shelf off the shores of Texas and Louisiana. The drilling and maintaining of offshore oil wells is a difficult and expensive operation necessitating the use of suitable operating platforms for positioning the required drilling or servicing equipment at a safe level above the surface of the waters in which drilling operations are being carried out.

At some locations off the coast of Louisiana, there is no solid bottom on which a platform may be set, or into which the legs (normally piles) of the platform may be driven. This is especially true at locations off the mouth of the Mississippi River where the water may be only 30 feet deep while the soft, fluid or unconsolidated mud underlying the water may be several hundred feet deep.

An offshore platform to be used in a muddy location of this type, for example, a small platform erected around a wellhead after the well has been drilled, may comprise a reinforced foundation member or template having a plurality of vertical tubular legs through which piling may be driven deep (200 to 300 feet) into the mud. Generally, there is sufficient skin friction between the mud and piles of this length to support the platform. However, a storm of considerable violence or duration can cause waves or a movement of the water tending to flex these long piles from side to side. This can result in a reduction in the skin friction effect between the mud and the piles so that the piles and platforms supported thereon sink deeper into the mud.

Various remedies have been tried to prevent piling and platforms supported thereon from sinking into the muddy ocean bottom. For example, at one wellhead a 15 ft. diameter steel caisson 45 feet high was positioned around the piling in a water depth of 25 feet so that ten feet of the caisson penetrated the mud and ten feet of it extended above the water level. Due to the extremely poor soil conditions at this well site, the caisson and piling sank 13 feet during a storm which produced 8 to 10 foot waves. The failure was caused by the impact loading from the waves which broke the skin friction on the piling to a degree sufficient to cause the structure to sink into the mud.

It is therefore a primary object of the present invention to provide an offshore platform having substantial lateral stability whereby its lateral movement during a storm is greatly minimized or entirely eliminated.

Another object of the present invention is to provide an offshore platform structure having an open framework above the ocean floor permitting water to pass readily through, while at the same time having additional bearing area in contact with the mud below the ocean floor

2

to absorb all or a portion of the lateral force caused by wind and wave and thereby lessen the otherwise required pile reaction.

A further object of this invention is to provide a method of erecting offshore platforms of the pile driven type having the characteristics outlined above.

These and other objects of this invention will be understood from the following description taken with reference to the drawing, wherein:

10 Figure 1 is an elevation of an offshore platform constructed in accordance with the present invention and shown as forming a well protector jacket or servicing platform around a wellhead.

15 Figure 2 is an elevation of an offshore platform provided with aligning means for driving batter piles therethrough.

20 Figure 3 is an isometric view of the reinforced sub-structure of Figure 1 which is provided with means for rendering the substructure substantially stable to lateral movement in muddy sub-soil.

25 Figure 4 is an elevation of the sub-structure of an offshore platform provided with removable stabilizing means.

Figure 5 is a plan view of a portion of the structure 25 illustrated in Figure 4.

Figure 6 is an isometric view of removable stabilizing means adapted to be used with a batter pile sub-structure of the type illustrated in Figure 2.

Referring to Figure 1 of the drawing, the sub-structure 30 11 of the present offshore installation is constructed in the form of a large template, preferably composed of a single section comprising a group of vertically-positioned, spaced, hollow steel columns 12 rigidly held together by structural bracing 13. The columns 12 are 35 normally made of a predetermined length of pipe or casing so as to extend from a desired height above the average wave level at the drilling location to a suitable point in the muddy ocean bottom. Preferably, as shown in Figure 3, at least four vertical columns are arranged 40 in a rectangle with the structural cross bracing members 13 so disposed that an open space is provided down through the center of the template to accommodate the necessary well casing 14 (Figure 1) rising out of the water. The top of the well casing 14 is closed by the 45 necessary valves contained in the casing head assembly or Christmas tree 15.

While a rectangular template 11 is preferred, it is realized that it may take any shape such as triangular, octagonal or even round, said template being composed of a minimum of at least three vertical legs. The internal 50 diameter of the tubular legs or columns 12 is large enough to accommodate piles 16 that are driven through the columns 12 and into the ocean floor.

These piles 16 may be from 200 to 300 feet in length 55 so as to support the sub-structure 11 and the platform 17 mounted thereupon. The weight of the sub-structure 11 and platform 17 is supported mainly by the skin friction between the mud and the outer surface of the piles 16 over its entire embedded length.

60 To provide lateral stability for the entire offshore foundation, the sub-structure 11 is provided with one or more plates of substantial area that are fixedly secured in a vertical position as by welding or bolting, between preferably at least two legs of the sub-structure.

65 The plates 18 are secured to the lower portion of the sub-structure 11 but their exact position thereon depends entirely upon the depth to which the sub-structure 11 is to be sunk into the mud. It is essential that at all times the plates 18 be positioned so as to be below the mud line on the lower portion of the sub-structure.

The plates 18 may be fixedly secured either to the vertical columns 12 or to any of the cross-bracing members 13 which may be positioned below the mud line. Although it is possible to use only one plate 18 provided it were positioned in a direction normal or transverse to the prevailing wave and wind forces, it is preferred that at least two plates 18 be affixed to the sub-structure 11 at an angle to each other, preferably at about a 90° angle, since there are few offshore locations where prevailing wind and wave forces act always from the same direction.

The exact size of the plates 18 depends on many factors, such as, for example, (1) the number of the plates employed, (2) the weight of the entire offshore platform structure to be stabilized (3) the area of the sub-structure and platform exposed to the wind and wave forces, and (4) the viscosity or solids content of the mud in which the installation is positioned. Thus, the thinner the mud the greater the tendency of the sub-structure to be moved by winds and waves thus necessitating the use of larger area plates. In a like manner, the greater the area of the sub-structure 11 that is exposed to the wind and wave elements, the greater the tendency for it to be tilted by the wind and waves and therefore the greater the need for larger plates to prevent this action.

Another form of the offshore structure is shown in Figure 2, wherein the template 21 comprises a plurality of vertical columns 22 and structural cross-bracing members 23 similar to those employed in the structure of Figure 1. In addition, it is provided with a plurality of tubular columns 24 sloping outwardly at an angle away from the center of the template 21 so as to give a broader base to the entire offshore structure. As illustrated in Figure 2, batter piles 25 are driven through the inclined tubular columns 24 down into the muddy ocean floor. If desired, piles may also be driven through the vertical columns 22. After the piles are driven in, a platform 27 may be positioned on top of the sub-structure 21. The stabilizing plates 28 may be either fixedly secured to the vertical columns 22 or to the inclined column 24, as shown.

As an example, it may be stated that in one offshore well location where piles were sunk about 225 feet into the mud, a 15 foot square template 11 was employed which was about 60 feet high and had four vertical plates mounted in a box-like arrangement as shown in Figure 3, the plates being 30 feet high. On the other hand, at another well location, a template 11 having four vertical piles and eight inclined or batter piles which template was 16 feet square and about 60 feet high only needed plates 25 ft. high because of the added resistance provided by the eight batter piles.

In positioning a sub-structure or template 11 (Figures 1 and 3) at a well site at an offshore location, the template 11 is carried to the location on the barge where it is hoisted in the air and lowered down around the well casing 14. Pressure is exerted in any suitable manner, as by placing weights on the top of the vertical columns 12, to force the lower portion of the template and the stabilizing plates 18 fixedly secured thereto into the mud so that the plates are entirely below the mud line, as shown in Figure 1, where they are not exposed to wind and wave forces. Piles 16 are then driven through the hollow vertical columns 12 deep into the mud and the template and piles are fixedly secured together in any suitable manner well known to the art, as by welding (not shown). A platform 17 may be attached after the tops of the piles have been cut off.

While the plates 18 (Figure 1) and plates 28 (Figure 2) are preferably fixedly attached to the vertical columns of the sub-structure, another sub-structure 31 (Figures 4 and 5) may be provided with guides or tracks 32 and 33 fixedly secured, as by welding, to the outer

surface of the vertical columns 34 so that a plate 38 could be dropped down in the tracks along the length of the sub-structure and then forced into the muddy ocean floor. The closed bottoms of the tracks 32 and 33 prevents the plate 38 from dropping further.

Instead of fixedly securing the plates 28 to the vertical or inclined columns 22 and 24, respectively (Figure 2), the plates 28 can be arranged in a skirt-like structure 40 (Figure 6) which can be dropped down over the outside of the vertical columns 22 and 24 prior to positioning the platform 27 on the sub-structure 21. Due to the inclined position of the columns 24, the skirt-shaped stabilizing means would be prevented from slipping off the bottom of the sub-structure. When this same type of a skirt-shaped stabilizing means is used on a sub-structure having only vertical legs, as shown in Figure 1, it is necessary to provide the necessary stop means at the bottom of the vertical columns 12 to prevent the stabilizing plate assembly from slipping off the bottom of the structure.

When a template in accordance with the present invention is positioned on the top of a muddy ocean bottom, there is normally sufficient body to the mud to support the template for the short period that it takes to drive pile. In locations where the mud is too thin, the template may be supported on side pontoons while pile is being driven through the template. The stabilizing plates increase the area of frictional resistance between the mud and the substructure thus helping to support the sub-structure while piles are being driven.

Although the present method of stabilizing platforms is particularly successful in locations where the piles cannot be driven to solid ground, the method works equally as well in stabilizing offshore platforms that are set on very long flexible piles that have a tendency to sway even though the bottoms thereof are anchored in the ocean floor.

We claim as our invention:

1. The method of constructing a permanent offshore foundation in an offshore location where the ocean floor underlying the water is soft and unconsolidated, said method comprising assembling at least three vertical tubular columns, connecting said columns in spaced relationship at points intermediate the ends thereof by cross-bracing to form a rigid structure, positioning plate means on said structure near one end thereof in a plane substantially parallel to the axis of said columns and fixedly secured against movement normal thereto, lowering the structure into the water with the columns positioned vertically and the plate means at the bottom portion of said structure, forcing said structure into the muddy ocean bottom until the plate means penetrate the mud line, inserting piles through said columns, forcing said piles into the muddy ocean bottom to a depth sufficient to support said foundation, and subsequently connecting said structure in supporting engagement with said piles.

2. The method of constructing a permanent offshore foundation in an offshore location where the ocean floor underlying the water is soft and unconsolidated, said method comprising assembling at least three vertical tubular columns, connecting said columns in spaced relationship at points intermediate the ends thereof by cross bracing to form a rigid structure, lowering the structure into the water with the columns positioned vertically, forcing the lower portion of said structure into the muddy ocean bottom, inserting piles through said columns, forcing said piles into the muddy ocean bottom to a depth sufficient to support said foundation, connecting said columns in support engagement with said piles, positioning plate means between at least two of said columns in substantially vertically movable engagement therewith and fixedly secured against movement normal thereto, and forcing said plate means downwardly to a point penetrating the mud line.

3. The method of constructing a permanent offshore foundation in an offshore location where the ocean floor underlying the water is soft and unconsolidated, said method comprising assembling at least three vertical tubular columns, connecting said columns in spaced relationship at points intermediate the ends thereof by cross bracing to form a rigid structure, lowering the structure into the water with the columns positioned vertically, forcing said structure into the muddy ocean bottom until the lower portion thereof is below the mud line, inserting piles through said columns, and forcing said piles into the muddy ocean bottom to a depth sufficient to support said foundation, connecting said columns in supporting engagement with said piles, surrounding said columns with substantially vertically-positioned plate means, and forcing said plate means downwardly to a point penetrating the mud line.

4. A permanent marine foundation having a high degree of lateral stability for use in offshore locations where the ocean floor underlying the water is soft and unconsolidated, said foundation comprising a substructure of at least three vertical tubular columns, said columns being disposed in horizontal spaced relationship to define a geometrical figure with a closed perimeter, cross-bracing means rigidly interconnecting adjacent columns, piles positioned within said columns and extending into the soft and unconsolidated ocean floor to a depth sufficient to support said foundation, said piles extending into the ocean floor below said substructure at least a length equal to the height of said substructure, means interconnecting said piles to said substructure, and substantially vertical plate means of substantial area secured to said substructure in the upper portion of said foundation, said plate means being affixed to said substructure so that said plate means extend continuously along at least one side of said substructure and are submerged in the muddy ocean bottom, whereby the substantial area of the plate means in the mud serves to anchor the foundation against lateral movement and absorb a substantial portion of the lateral forces caused by wind and wave forces.

5. A permanent marine foundation having a high degree of lateral stability for use in offshore locations where the ocean floor underlying the water is soft and unconsolidated, said foundation comprising a substructure of at least four batter tubular columns, said columns being disposed in horizontal spaced relationship to define a geometrical figure with a closed perimeter, cross-bracing means rigidly interconnecting adjacent columns, piles positioned within said columns and extending into the soft and unconsolidated ocean floor to a depth sufficient to

support said foundation, said piles extending into the ocean floor below said substructure at least a length equal to the height of said substructure, means connecting said piles to said substructure, and plate means of substantial area secured to said substructure in the upper portion of said foundation, said plate means being affixed to said substructure so that they extend continuously along at least two sides of said substructure and are submerged in the muddy ocean bottom, whereby the substantial area of the plate means in the mud serves to anchor the foundation against lateral movement and absorb a substantial portion of the lateral forces caused by wind and wave forces.

6. A permanent marine foundation having a high degree of lateral stability for use in offshore locations where the ocean floor underlying the water is soft and unconsolidated, said foundation comprising a substructure of at least four vertical tubular columns, said columns being disposed in horizontal spaced relationship to define a geometrical figure with a closed perimeter, cross-bracing means rigidly interconnecting adjacent columns, piles positioned within said columns and extending into the soft and unconsolidated ocean floor to a depth sufficient to support said foundation, said piles extending into the ocean floor below said substructure at least a length equal to the height of said substructure, means connecting said piles to said substructure, and substantially vertical plate means of substantial area secured to and surrounding said substructure in the upper portion of said foundation, in the form of a skirt, said plate means being affixed to said substructure so that they are submerged in the muddy ocean bottom, whereby the substantial area of the plate means in the mud serves to anchor the foundation against the lateral movement and absorb a substantial portion of the lateral forces caused by wind and wave forces.
